DISPLAY DEVICE

George T. Chapman, Detroit, Mich.

Application January 18, 1940, Serial No. 314,439

13 Claims. (Cl. 40—104)

This invention relates to a display device for automatically turning the leaves or pages of newspapers, magazines and the like.

An important object of the invention is to provide a device which will, at predetermined intervals, singly turn the leaves of a magazine or the like in a direction counterclockwise to the reader and when every sheet has been so turned, will, in one motion, return the magazine or the like to its initial position with the cover displayed.

A further object of the invention is to provide a leaf turning mechanism which will automatically return the magazine to initial position after the last sheet has been turned regardless of the number of pages in the magazine. No adjustment is required to accomplish this.

A further object of the invention is to provide a leaf turning mechanism which will turn the pages of a magazine while retaining them substantially in plane.

A further object of the invention is to provide a leaf turning mechanism which will not alter or mar any portion of the pages upon which it operates.

Other objects and advantages will be apparent from the following description.

In the drawings:

Fig. 1 is a perspective view of the device.

Fig. 2 is a section along the lines 2—2 of Fig. 3. It is a vertical section from front to back of the cabinet and with the magazine rotated to a horizontal position.

Fig. 3 is a section along the lines 3—3 of Fig. 2.

In Fig. 1 the complete device may be seen in perspective. A magazine 10 is in position upon a cabinet 11. It is the aim of the invention to provide a device which will display each page of the magazine or a like article. An arm 15 and a suction cup 14, actuated by means to be described herein, singly turn the pages of the magazine. Means will also be described herein to return the magazine 10 to initial position with its cover displayed after all the pages have been turned.

Looking at the detail construction of the device, bent pins 12 and thumb nuts 13 hold the magazine in place by engaging it along its line of binding. The axis 16 about which the arm 15 rotates, is to the left of the center of the magazine. This causes the suction cup to slide toward the edge of the page when the arm is rotated thus causing the page to be taut or in plane during its rotation. The suction cup will finally slide off the edge of the page and release said

page. In the preferred construction this occurs when the page has been rotated 130 degrees.

The details of the mechanism can best be observed in Figs. 2 and 3. In Fig. 2, a motor 17, mounted on a frame 18, rotates an eccentric 19 which reciprocates a piston 20 in a cylinder 21. The cylinder is pivotally mounted by a pin 31 on frame 18 to allow for the eccentric movement of piston 20. Cylinder 21 is provided with an intake valve 22 and an exhaust valve 23. A conduit 24 leads to the intake valve. At its other end, conduit 24 is fastened to a tube 25 leading to a hub 26 of hollow arm 15 on which suction cup 14 is located at the free end. The piston 20 and valves 22 and 23 are arranged to create a suction in suction cup 14 and thus cause the magazine page to adhere to cup 14.

A motor shaft 27 of motor 17, through a key 28, drives a stud 29 on which is fastened block 30. Bolted to block 30 are arms 31 which are adapted to engage and rotate a cam wheel 32. Rigidly fastened to cam 32 is a gear 34 which meshes with a gear 35 which has the same axis as arm 15 and is fastened thereto. Therefore, contact of arms 31 on cam 32 rotates the latter through an arc which, through gears 34 and 35, rotates arm 15 and suction cup 14. As soon as an arm 31 has left cam 32, a torsion spring 36, fastened to the axis of arm 15, and to the frame 18 of cabinet 11, returns cam 32, arm 15 and suction cup 14 to their original positions. In the preferred design the motor is designed such that arm 15 is actuated by cam 32 about every thirty seconds. This procedure automatically continues turning each individual page at intervals until every page, including the back cover has been turned.

Means are provided so that when the back cover has been turned the magazine or book will be automatically turned back to initial position with the front cover displayed so that the page turner may repeat (see Fig. 3). When the last page (i. e. back cover) of the magazine has been turned, the suction cup is returned as usual by torsion spring 36. This brings suction cup 14 directly in contact with the cabinet 11. The surface of cabinet 11 is provided with a hole 38 directly beneath the point of contact of the suction cup. Connected to hole 38 is a conduit 39 leading to a cylinder 40 containing piston 41. A piston rod 42 on piston 41 projects downwardly out of cylinder 40. Contact of the suction cup over hole 38 causes air to be withdrawn from conduit 39 and a low pressure to be created above piston 41 in cylinder 40. Piston 41, therefore,

moves upward. An arm 43 is pivoted at 44 and at its free end rests on a lug 45 of piston rod 42. A tooth 46 on arm 43 is adapted to engage a ratchet wheel 47 mounted on a shaft 48. A sprocket 49 is keyed to shaft 48 and driven by a chain 50 from a sprocket 51. Sprocket 51 is keyed to a shaft 52. The housing of motor 17 contains gears (not shown) which drive shaft 52 from the motor shaft 27. The two shafts 27 and 52 project from the front of the housing. In the preferred construction shaft 52 makes four revolutions to one revolution of shaft 27. The numeral 53 designates an idler sprocket which also engages chain 50. A connecting rod 54, pivotally connected to arm 43 at 44 and to a link 55 by 15 a pivot 56, is slidably mounted in guide pins 57. Link 55 is pivotally connected to a crank 58 which is keyed to a shaft 59.

When piston 41 moves upward, as previously explained, it lifts arm 43 by means of lug 45 on piston rod 42. Tooth 46 of arm 43 engages ratchet wheel 47 which is rotated by chain 50 and sprocket 49. This slides arm 43, connecting rod 54, and link 55 to the left as seen in Fig. 3. Crank 58 is, therefore, rotated in a clockwise direction preferably about 26 degrees. Crank 58 rotates shaft 59. A sprocket 60 is also keyed to shaft 59 and engages a chain 61 which drives a sprocket 62. Sprocket 62 is keyed to a shaft 63 (Fig. 2). Mounted on shaft 63 is an arm 64 adapted to shift the magazine to initial position. Arm 64 when not in operation is preferably flush with the upper surface of the cabinet. Motion of shaft 63 through sprocket 62 and chain 60 actuates arm 64. In the preferred embodiment arm 64 is rotated 90 degrees by shaft 63. In Fig. 3, arm 64 is shown in dotted lines in operative position. A spring 65, mounted on crank 58 and on frame 18 by a lug 66 returns the arm 64 to its rest position after it has rotated 90 degrees and tooth 46 on arm 43 has slipped out of engagement with ratchet wheel 47.

It should be noted that when arm 64 is actuated to close the magazine, the arm 15 is in the position shown in Fig. 3 with suction cup 14 on the opening 38. There is thus no opportunity for the arms to interfere with each other. The pages of the magazine returned by arm 64 do, however, fall on suction cup 14 and a portion of arm 15. Hole 38 is preferably located near the edge of the magazine. The torque transmitted to arm 15 from motor 17 is sufficient to overcome the weight of the returned pages and flex them to permit arm 15 to pivot. The device is, therefore, particularly adapted to be used with magazines or the like provided with flexible pages and a flexible rear cover.

Arm 15 and suction cup 14 now repeat the previously explained turning of the pages.

It is to be understood that the particular structure described is but a preferred embodiment of my invention.

What I claim is:

1. In a leaf turning mechanism, a support for a plurality of leaves, a movable arm associated with said support for turning individual leaves in one direction, means for moving said arm at predetermined intervals, said arm having a hole formed at a free end thereof, means creating a suction at said hole whereby a leaf may be held to said arm, repositioning means for shifting a plurality of leaves back to a starting position, actuating means for said repositioning means, and means for initiating the movement of said actuating means comprising a cylinder associ-

ated with said support and located to register with said hole in said arm, and pressure responsive means operably connected with said actuating means within said cylinder arranged to be actuated by suction from the hole in said arm when all of said leaves have been individually shifted.

2. In a mechanism for turning a plurality of leaves from an initial position to a turned position, a support for a plurality of leaves, means on said support to clamp the edges of said leaves whereby an axis of rotation of said leaves is formed, a movable arm associated with said support pivoted on an axis substantially parallel with said leaf axis but spaced therefrom, holding means on a free end of said arm for slidably retaining an individual leaf, said axes being so spaced relative to the length of said arm that said holding means will be freed from a leaf when said leaf has moved through a predetermined angle beyond a vertical position.

3. In a leaf turning mechanism, a support for a plurality of leaves, a movable arm associated with said support for turning individual leaves in one direction, means for moving said arm at predetermined intervals, said arm having a hole formed at a free end thereof, means creating a suction at said hole whereby a leaf may be held to said arm, repositioning means for shifting a plurality of leaves back to a starting position, actuating means for said repositioning means comprising a motor, a rotating shaft on said motor, a rotating ratchet wheel powered from said motor shaft, a dog adapted to engage said ratchet wheel, a longitudinal shifting bar adapted to be shifted by contact of said dog in said ratchet, crank means adapted to transfer longitudinal shifting means of said bar to said repositioning means, and means to cause engagement of said dog with said ratchet comprising a piston and a cylinder exposed to suction of the free end of the rotatable arm when all leaves have been turned.

4. In a mechanism for turning a plurality of leaves from an initial position to a turned position, a movably mounted member, a suction cup thereon, means to actuate said member to effect individual turning of said leaves by reason of contact of said suction cup therewith, and suction responsive means actuated by contact of said suction cup when all leaves have been turned from initial position, to shift all turned leaves to initial position.

5. In a mechanism for turning a plurality of leaves from an initial position to a turned position, a movable member, a suction cup thereon, means to actuate said member to effect individual turning of said leaves, an open conduit concealed beneath leaves in the initial position, and suction responsive means actuated by contact of said suction cup with the open end of said conduit to shift all turned pages to initial position.

6. In a mechanism for turning a plurality of leaves from an initial position to a turned position, a movably mounted member, a suction cup thereon adapted to adhere to individual leaves, means to actuate said member to turn said leaves individually, means to maintain a suction in said cup, a cylinder, a piston within the cylinder, a piston rod on said piston, mechanical means adapted to be actuated by said piston rod to shift all turned pages to initial position, a conduit connected to said cylinder and provided with an open end adapted to be concealed be-

neath leaves in the initial position and adapted to be contacted by said suction cup when said pages have been turned whereby said piston and rod are actuated and said pages are returned to initial position by said mechanical means.

7. In a mechanism for turning a plurality of pages from an initial position to a turned position, a movable member, a suction cup thereon, a first means to actuate said member to effect individual turning of said pages by reason of contact of said suction cup therewith, a second means to create a suction in said cup, and a third means to simultaneously return all turned pages to initial position when all pages have been turned, said third means comprising a rotatable member positioned below all of said turned pages and means to actuate said rotatable member.

8. In a mechanism for turning a plurality of pages from an initial position to a turned position, a movable member, a suction cup thereon, means to actuate said member to effect individual turning of said pages by reason of contact of said suction cup therewith, means to create a suction in said cup, a conduit concealed beneath pages in the initial position, and suction responsive means actuated by contact of said suction cup with the open end of said conduit, when all pages have been turned from initial position, to shift all turned pages to initial position.

9. In a mechanism for turning a plurality of pages from an initial position to a turned position, a movable member, a suction cup thereon adapted to adhere to an individual page to be turned, a first means to create a suction in said cup, a second means to move said member at predetermined intervals and thereby turn an individual page, and a third means adapted to simultaneously return all pages to the initial position after the last page has been turned, said third means comprising a second member adapted to lift all turned pages as a unit.

10. In a mechanism for turning a plurality of leaves from an initial position to a turned position, a movably mounted arm, a suction cup

thereon, means to actuate said arm to effect individual turning of said leaves by reason of contact of said suction cup therewith, said means comprising a motor, a rotating shaft on said

5 motor, arms extending from said shaft, a cam wheel adapted to be rotated by contact of said arms and means for transmitting rotation of said cam to said movably mounted arm.

11. In a mechanism for turning a plurality of 10 leaves from an initial position to a turned position, a movably mounted member, means on said member adapted to adhere to individual leaves, means to actuate said member to effect individual turning of said leaves and means actuated 15 when all leaves have been turned from initial position to shift in a unit all turned leaves to initial position.

12. In a mechanism for turning a plurality of leaves from an initial position to a turned position, a movably mounted member, a suction cup 20 thereon, means to actuate said member to effect individual turning of said leaves by reason of contact of said suction cup therewith, said member being movable on an axis parallel with but 25 spaced to one side of the axis of said leaves and having a length whereby it will contact the leaves in one extreme position and clear them in the other extreme position thereby causing said suction cup to slip from the outer edge of the leaf 30 being turned at a predetermined point in its movement beyond a vertical position.

13. In a mechanism for turning a plurality of leaves from an initial position to a turned position, a movably mounted member, means thereon 35 adapted to adhere to individual leaves, means to actuate said member to effect individual turning of said leaves by reason of contact of said adhering means therewith, means mounting said member on an axis parallel with but to one side 40 of the axis of the leaves thereby giving a movement adapted to release the adhering means from the leaf being turned at a predetermined point in its movement after the leaf has been turned more than ninety degrees.

45 GEORGE T. CHAPMAN.
